UNITED STATES PATENT OFFICE.

ISAAC BERNSTEIN, OF ALAMEDA, CALIFORNIA.

UNION OVERALLS.

1,426,540.

Specification of Letters Patent. Patented Aug. 22, 1922.

Application filed September 18, 1919. Serial No. 324,531.

To all whom it may concern:

Be it known that I, ISAAC BERNSTEIN, a citizen of the United States, residing at Alameda, in the county of Alameda and State of California, have invented certain new and useful Improvements in Union Overalls, of which the following is a specification.

My invention is a union overalls which 10 may be slipped on and off and opened in the back quickly.

Referring to the annexed drawing:

Figure 1 is a front perspective view of my overalls shown on a man.

15 Figure 2 is a rear perspective view of my overalls shown on a man.

Figure 3 is a fragmentary rear view of my overalls with the flap open.

20 Figure 4 is a fragmentary front view of my overalls.

In the drawing 1 indicates the body, 2 the trousers and 3 the sleeves of my overalls. The back of the body has an entrance 4 extending from the crotch 5 through the 25 collar 6 at the left side of the back thereof and a flap 7 which extends from the left side to the right side of the back of the body and closes said entrance. The ends of the collar 6 at the entrance 4 are buttoned together by a button 8 on the end of the collar which is on the body 1 and a button hole 9 in the other end of the collar which is on the flap 7. A suspender strap 10 extends from the upper right corner of the flap 7 30 over the right shoulder of the wearer and is buttoned over the upper edge of a pocket 11, on the front of the body 1 at the right side thereof, by means of a button 12, sewed to the front of the body and a button hole 40 13 in the extremity of the strap. The upper edge of the front wall of pocket 11 is buttoned over button 12 under strap 10 through button hole 12' in said wall at its upper edge, closing the entrance to said 45 pocket. A strap 14 of the same style as strap 10 is sewed at one end to the left shoulder and is buttoned over the upper edge of a pocket 15 on the front of the body 1 at the right side thereof by means of a button 16, sewed to the front of the body and a button hole 17 in the extremity of the strap, the upper edge of the front wall of the pocket being buttoned on said button 50 through a button hole 16' in said front wall at its upper edge, closing the entrance to said pocket.

The two straps 10 and 14 have the appearance of suspenders. The right edge of the flap 7 may be buttoned near the under side of the right sleeve by means of a button 17 sewed at such point to the back of the body 1 and a button hole 18 in the flap near its right edge. An elastic belt 20 is sewed in the waist of the body 1 and flap 7, the ends of which meet at the right edge 60 of the flap when the flap is closed and may be hooked together by a hook 21 on one end and an eye 22 on the other end thereof, whereby the garment is gathered around the waist to fit persons of various sizes. Pockets 70 23 and 24 are formed on the inside of straps 10 and 14, the bottom of said pockets being near the extremity of the strap. The entrances of said pockets are closed by flaps 25 and 26 which may be closed by snap 75 buttons 27 and 28 on the flaps and pocket walls. The trousers 2 are formed with the usual fly 29 in front. A back pocket 30 is formed on the rear of the trousers and front trousers pockets 31 and 32 are formed 80 on the front of the trousers respectively at the opposite sides thereof. The trousers are also provided with side slits 33 through which the wearer has access to his regular trousers pockets. In the lower ends of the 85 trousers 2 are elastic bands 34 for gathering the trousers ends around the ankles of the wearer. In the ends of the sleeves 3 are elastic bands 35 for gathering the sleeve ends around the wrists of the wearer. 90

The strap 10 buttoned on button 12 is sufficient to hold the flap 7 in closed position and the overalls on the wearer for quick use.

I manufacture my overalls in three sizes 95 which by means of the elastics 34 at the lower ends of the trousers, and the elastics 35 at the ends of the sleeves will fit persons of all sizes.

Having described my invention, I claim: 100

1. Overalls including a body, trousers, and sleeves, the body being formed with an entrance in the back extending from the crotch to the collar, a single flap for closing said entrance, a suspender strap at the upper corner of said flap extending over a shoulder of the wearer, and means for fastening said strap to the front of the garment. 105

2. Overalls including a body, trousers, 110 and sleeves, the body being formed with an entrance in the back extending from the

crotch to the collar, a flap for closing said entrance, a front pocket, a button for buttoning the entrance of said pocket, a suspender strap at the upper corner of said flap extending over a shoulder of the wearer, said strap having a button hole whereby it is buttoned on said button.

3. Overalls including a body, trousers, and sleeves, the body being formed with an entrance in the back extending from the crotch to the collar, a single flap for closing said entrance, means for detachably fastening the ends of the collar together at said entrance, and means for detachably se-

curing the upper corner of said flap to said body.

4. Overalls including a body, trousers, and sleeves, the body being formed with an entrance in the back extending from the crotch to the collar, a single flap for closing said entrance, means for detachably fastening the upper corner of said flap to said body, and means for detachably fastening said flap to the back of the body near the underside of one of the sleeves of the garment.

In testimony whereof I affix my signature.
ISAAC BERNSTEIN.
